(54) **WINNOWING MILL, MACHINERY**

(76) Inventor: **James Ruple**

James Purple of Washington, State of Pennsylvania.

Letters Patent.

The schedule referred to in these Letters Patent and making part of the same containing a description in the words of the said James Purple himself of his improvement in the machinery of Winnowing Mills.

To all to whom these presents shall come.

Be it known that I, James Purple of Washington, Washington County, State of Pennsylvania, have invented a new and useful improvement in the machinery of Winnowing Mills for the purpose of cleaning grain from chaff, chaff, chaff &c and that the following is an exact description of the construction and operation of the said machine as improved by me.

The body of the mill is formed by making two sides, each to be four feet high, four feet in length, and from three to three feet six inches deep, the back part of the side, formed in a half circle and covered with a hoop, or board, nailed on the outer part of the circle; this circle to be from two feet six inches to three feet in diameter, cut an air hole in the centre of the circle in the mill side, of from six to eighteen inches in diameter; make a back and front frame of small scaulding, the frame to be about two feet two inches between the upright posts, the post to be about four feet long with a cross rail at the top and bottom, in these frames fasten the sides, place the frames about three feet apart, the back frame to cover the centre of the before mentioned circle; on the right hand side of the back frame, place an additional upright post so as to admit the east wheel to run between the posts; make a sun shaft, two feet two inches in length, and two & a half inches square; in one end of this shaft insert a quidgeon, projecting about six inches, and in the middle of the projecting part of the quidgeon, fasten a small pinion, about three & a half inches in diameter, that will work in a cog wheel, above which must be four times as large as the pinion in the other end of the shaft a quidgeon is inserted, projecting two and a half inches upon which a crank one and a half inch is made, place this shaft in the posts of the back frame in the centre of the aforesaid circle, and in the shaft, there are pins to be placed of a suitable size, to play instead of the circle or drum, upon a small shaft, about two feet in length, with a round tenon upon each end, the tenon

to be put in brackets and fastened to the left side of the mill three inches back of the front frame, upon this small shaft place three pitman cranks, the left one to give motion to the shoe, the middle one to receive a stretcher from the crank on the fan shaft the lower one to give motion to the screen below the shoe from the shaft by means of the aforesaid stretcher the shoe and screen (hereafter described) is put in motion, making the shoe three feet in length, the back part to be four inches wide, with a board one foot seven inches wide nailed on the bottom, inclined forward, the front part one foot wide, with grooves cut in the sides to receive the riddle, the shoe about one foot seven inches wide; on the top of the shoe and five inches from the fore end, fasten a strip oak and a fourth inch square; one foot from inches from the front frame, and four inches from the top of the side, place a piece of board, across the mill, with a pin in the centre; make a hole in the back part of the shoe bottom, and suspend the shoe by placing it upon the cross strip at the back part, and a strap fastened to the front strip, and the top rail of the front frame, fasten a piece of iron in the shoe opposite the upper pitman crank, on the small shaft, & attach it to the same; make a screen, one foot eight inches wide, and five feet long, with side pieces, one inch square, the end piece at the top, to be six inches wide, and the bottom piece one foot wide, cover it with cockle, and chip, screen, rest the bottom upon the cross rail of the back frame, near the lower part of the mill, put a pin in the lower cross piece of the screen frame, to rest in a mortise in the cross rail to support the screen, suspend the screen in front, below the riddle in the shoe, through which the grain passes, giving it a sufficient inclination, to insure the passage of the grain, and discharge it at the back end of the mill, thus discharging the chaff, at one end, and the grain at the other end, fasten a piece of iron on one side of the screen frame four inches long & one broad, with a joint in it near the screen frame, and a pin in the outer end to fit in a hole in the lower pitman crank, on the small shaft, thus when the mill is put in motion the shoe and screen will shake from one side of the mill, to the other, and strips should be placed under the shoe, to prevent the grain from scattering over the sides of the screen, when it is shaking, the screenings are received in a box, front by boarding the bottom of the mill, with a slide in front, place a hopper on the top of the mill, over the bottom board of the shoe, close the openings with bags fitted to the hopper, when the screen is not to be used, take it out of the mill, and place a slide board upon strips or grooves, cut in the sides of the mill.

to discharge the grain at the back part of the mill.

Fasten a crank one foot long upon the outer end of the quadrants, in the large cog wheel and upon this crank fast a handle and by turning the crank, the whole machinery is put in motion.

P. S. On the sides of the screen frame, and twenty one inches from the bottom of the frame, nail on blocks of such width, that by shaking the screen, they will strike the sides of the mill, and give the screen the same motion at the bottom that it has at the top.

What I claim as new, and of my own invention or discovery, in the above described machine, and for the use of which I claim an exclusive privilege, is the formation of the screen and the manner of shaking and using it, and the curst boards under the shoe to prevent the grain from scattering.

Witness,

James B. Rupple
John Marshall
